UNITED STATES PATENT OFFICE.

FREDRICK P. ANGELL, OF BATTLE CREEK, MICHIGAN, ASSIGNOR TO
AMERICAN COLUMN COMPANY, (LIMITED,) OF BATTLE CREEK,
MICHIGAN.

STAPLING-MACHINE.

No. 826,081.

Specification of Letters Patent.

Patented July 17, 1906.

Application filed May 31, 1905. Serial No. 263,169.

To all whom it may concern:

Be it known that I, FREDRICK P. ANGELL, a citizen of the United States, residing at Battle Creek, in the county of Calhoun and State of Michigan, have invented certain new and useful Improvements in Stapling Machines; and I do hereby declare the following to be a full, clear, and exact description of the invention, such as will enable others skilled in the art to which it appertains to make and use the same, reference being had to the accompanying drawings, and to the marks of reference placed thereon, which form part of this specification.

15 My invention relates to machines for driving staples within the adjacent edges of staves comprising a wooden column from the interior thereof; and the object of the present invention is to so construct a machine for the purpose that a column built therewith will be very rigid and substantial, whereby the work can be speedily performed, and whereby the machine will be comparatively simple in construction, positive in operation, and 25 easily manipulated.

Other objects and advantages will herein-after appear in the novel construction, combination, and arrangement of parts described and claimed, and illustrated in the accompanying drawings, wherein—

Figure 1 is a sectional longitudinal view showing the machine in readiness for placing a column on the stapling mandrel or anvil. Fig. 2 is a rear end elevation. Fig. 3 is a detail side elevation of the staple-feeding mechanism. Fig. 4 is a detail front elevation of the presser-foot head with the presser-foot nearly elevated. Fig. 5 is a detail front elevation of the presser-foot head with the presser-40 foot at a downstroke. Fig. 6 is a longitudinal cross-section of the presser-foot. Fig. 7 is a detail longitudinal section of the anvil with the cap removed and shows the staple-driving bar in position for forcing a staple 45 within a column or other article placed on said anvil as in Fig. 9. Fig. 8 is a plan view of Fig. 7 with the cap intact. Fig. 9 is an end view of the anvil with the end cap removed and shows the staple-driving slide 50 with a staple driven within the adjoining edges of two staves comprised within a column. Fig. 10 is a cross-section of an anvil

with a staple in the staple-holding channel. Fig. 11 is an end view of the anvil with the end cap intact. Fig. 12 is a detail view of 55 the staple-driving reciprocating bar. Fig. 13 is a perspective view of the cam for operating the reciprocating staple-driving bar. Fig. 14 is a perspective view of the staple-driving slide. Fig. 15 is a perspective section of a wooden column banded preparatory for driving staples to secure the same together, and Figs. 16 and 17 are perspective views of staples employed upon the machine.

A represents the standard to the machine; 65 B, an overhanging arm; C, the drive-wheel; D, the main shaft; E, the column-holding anvil and staple-receptacle; F, the staple-feeding mechanism, and G a pieced wooden column.

The arrows indicate the revolving direction of the operating parts.

The standard A has a forwardly-projecting foot, as shown, with a widened flange for securing the same to a floor by means of bolts or lag-screws, the foot portion being aligned with the anvil E and arm B to counterbalance the machine. The arm B may comprise a part integral with, but by preference is secured to the standard by means of bolts- 75 as shown. Within this arm the operating, shaft D is revolutely secured at either end in boxes, as shown. At a point below the arm and aligned therewith the detachable steel anvil E is secured. This anvil is tapering and 80 fitted within a corresponding-shaped hole through the standard and secured in place by means of set-screws 1, the upper face of the anvil preferably being parallel with the floor.

As shown in Fig. 10, the anvil has a longitudinal groove comprising a series of different widths, the upper portion of the groove being the widest and shaped to form ledges on either side for seating a cap H. Below this cap the groove is formed to provide a staple-holding receptacle or chamber I, and below the chamber the groove is narrowed and forms a guideway for a reciprocating staple-driving bar J. This bar is longitudinally grooved along its top and bottom edges and adapted to receive a small wire cable 4, which runs over grooved rollers 5 and 6, the former being located within an aperture near the forward end of the bar, the latter being sus-

pended below the bar between ears 7 depending therefrom, as shown. Secured at one end of the cable and adapted to slide within the chamber I above the bar a staple-carrier 8 is provided, the opposite end of the cable passing over the pulleys 5 and 6 and winding about a spool actuated by a rack-and-gear mechanism F, hereinafter more fully set forth. Within the forward end of this bar a wedge-shaped sliding cam 9 is secured, and it is adapted to work through a slot 10 (see Figs. 1 and 7) in a cap-piece 11, screwed on the end of the anvil E. This cap-piece is grooved out at its inner side and when fitted to the end of the anvil provides a slot 12, within which the staple-driving slide 13 is adapted to work. The staple-driving slide comprises a rectangular metallic piece having a longitudinal sloping-topped aperture 14, through which the cam 9 is adapted to play, the slope of the aperture being adapted to fit the tapering side of said cam. The upper or face side of this slide is alined with the bottom of chamber I when in a normal or lowered position, so that a staple when forced forward by the carrier 8 will lodge upon the top thereof, as shown in Fig. 1.

Within the chamber I, above the staple-driving bar J, the staples 15 are distributed side by side with their points upwardly and transverse to the cross-section of the anvil E, as shown, and fitted above the staples within the widened mouth of the chamber I the chamber-covering cap H is fitted, its forward end terminating even with the end of the anvil, as shown in Fig. 8.

To the rear end of the staple-driving bar a pin 16 is transversely fixed and engages the lower extremity of an actuating-lever 17. This lever works from a bracket 18, bolted to the standard of the machine, and its upper extremity is provided with a friction-roller 19, engaging with a rotary cam 20 on the driving-shaft. From the axle 21 of said lever an arm 22 extends, to the extremity of which a coil-spring 23 is hooked, and engages at its opposite extremity with a hook 24, bolted to the machine. The object of the spring is to keep the friction-roller 19 always in engagement with the cam 20. The cam 20 is formed with an abrupt spiral-shaped race and is adapted to cause the lever 17 to oscillate when the shaft D rotates. At the opposite end of the shaft an internally-milled cam 24 is fitted. This cam has a spiral-shaped groove 25, within which a friction-roller 26, secured to a cross-head 27, is adapted to work. The shape of the groove is such that the roller 26 will be forced to the center of the cam when rotated toward the right, as shown in Fig. 5, and release said roller upon a further rotation thereof. A coil-spring 28, placed about the upper extremity of the cross-head, fixed between an eyelet 29 of the bracket 30 and a collar 31 to the cross-head,

causes the roller 26 to regain its normal position within the cam, and that the roller will not strike the cam abruptly on its return movement upward I provide a strap 37, one end of which is secured to the collar 31, its opposite end passing about the periphery of the cam and fastening to the eyelet 29. This strap is taut about said cam when the cross-head is in an elevated position and slack when in a depressed position, as shown in Fig. 5. The stem to the cross-head works vertically to the axis of the driving-shaft through eyelets 29, 32, and 33 of the bracket 30. At either side of the friction-roller 26 and adapted to bear against the face of the rim to the cam 24 friction-rollers 35 are secured to the cross-head by studs 36. These rollers prevent the cross-head from turning in its bearings and always keep the friction-roller 26 in working position with the cam. Within the lower extremity of the cross-head a longitudinal bore is provided and forms an air-chamber 38, within which a piston 39 is fitted, and that the piston will keep its position within the cross-head a longitudinal slot 40 is made in the side of the air-chamber, near the bottom thereof, and a pin 41 screwed within the piston and adapted to work within said slot. The lower end of the piston is provided with a longitudinal threaded hole, within which the threaded shank of the presser-foot 42 is fitted, a lock-nut 43 being placed thereon to secure said presser-foot from turning after having been located in a working position.

The staple-feeding wire 4 is operated by a gear mechanism F, bolted to the rear of the machine, as shown. The mechanism chiefly consists of a spool 44, to one end of which a spur-gear 45 is attached, a larger gear 46 meshing therein. A small gear 47 is secured to the axle of the gear 46, and a rack 48 meshes with the gear 47, said rack being longitudinally operative through ways in the extremities of arms 49, said arms forming a part of the bracket 50. The spool and its driving-gear 46 are supported on axles revolute in a common plane from arms 51 of the bracket 50. To the upper extremity of the rack 48 a weight 52 is secured and causes the rack to actuate the gear mechanism and wind the cable 4, by which means the staples within the chamber I of the anvil E will be fed to the staple-driver as the machine is operated.

To one side of an upper arm of the mechanism F a gong 53 is secured, and an arm carrying a hammer 54 is pivotally attached in such manner that when the weight 52 descends it will hit the arm and cause the hammer to strike the gong. By this provision the operative will be informed when the staples are exhausted, and thereby cautioned to replenish the machine with staples, the staple-feed slide 8 being engaged in such manner that when the wire cable 4 has coiled

about the drum 44 and moved the slide to the outer extremity of the anvil the weight 52 will ring the gong.

5 A foot-lever 55, conveniently located near the extremity of the anvil, gives the operative control of the machine. To the opposite end of the foot-lever shaft a crank 56 is attached. This crank connects with a tripping-lever 57, pivoted to the extremity of an arm on the bracket 18 through the medium of a connecting-rod 58, and a dog 59, operative from a collar 60, secured to the driving-shaft, engages the tripping-lever 57 to operate the machine.

15 The driving-wheel C is loose on the shaft and only actuates the machine when the foot-lever throws the dog 57 in engagement therewith, the mechanism for the purpose not differing from that used on power-presses for a 20 like purpose.

The operation of the machine in the main will have been apparent from the foregoing description. Staples having been supplied to the receptacle I within the anvil E and the 25 cap H having been placed to close the staple-feeding chamber, the staple-feeding guide 8 being brought to bear against the staples, a column G is placed over the anvil so that two adjoining edges of staves thereof will be 30 alined with the upper face of the anvil. The foot-lever 55 being depressed will cause the dog 57 to lock the driving-wheel C to the shaft D. As the shaft revolves the cam 24 will move the presser-foot 42 downward and 35 hold the column firmly against the anvil at a point immediately above where the staple will be driven. The cam 20 will likewise revolve with the shaft D and move the lever 17 and cause the staple-driving bar J to slide 40 inwardly, by which means the cam 9 will raise the slide 13, carrying a staple, and force the prongs thereof inwardly within the adjoining edges of the staves comprising the column and prevent the same from separating. 45 The mechanism can be stopped as each staple is driven, as may be deemed expedient, it being necessary to slide the column along on the anvil as the work progresses, so that the column may be stapled the whole length 50 thereof. One row of staples having been driven, the column is rotated on the anvil sufficiently to permit a second and succeeding row of staples to be driven until the column is finished.

55 It will be apparent that various changes in the form and minor details of construction could be resorted to without departing from the spirit or sacrificing any of the advantages of my invention, and I hold myself as entitled to such minor changes in its construction as compatible with the spirit of my improvements.

Having described my invention, what I claim as new, and desire to secure by Letters 65 Patent, is—

1. In a stapling-machine, the combination of a framework having an outwardly-extending arm, a revolute shaft supported by said arm, a vertically-reciprocating cross-head carrying a presser-foot operative by said shaft at the outer end of said arm, a tapering anvil having a narrow-bottomed, longitudinal groove in its upper face, with an upper widened apartment forming a staple-holding receptacle, alined with and supported by 70 said framework below said arm, a reciprocating bar operative within the bottom of said groove, a cap to said receptacle, a vertical actuated staple-driving slide operative by said reciprocating bar at the outer extremity of 80 said anvil, means to feed staples from said staple-holding receptacle to said staple-driving slide, means to actuate said reciprocating bar from said revolute shaft, said presser-foot and said staple-driving slide being adapted to 85 approach each other when driving a staple and recede from each other when said staple has been driven, all adapted to coact substantially as, and for the purpose set forth.

2. In a stapling-machine, the combination 90 with a framework having an outwardly-extending arm, a revolute shaft supported by said arm, a drive-wheel and an external cam operative at one end of said shaft, an internal cam operative at the opposite end of said 95 shaft at the outer extremity of said arm, a vertically-reciprocative cross-head carrying a presser-foot operative at the outer end of said arm by said internal cam, a portable tapering anvil having a narrow-bottomed, 100 longitudinal groove in its upper face, with an upper widened apartment forming a staple-holding receptacle, alined with and supported by said framework below said arm, a reciprocating bar operative in said groove, a vertical 105 staple-driving slide operative by said bar at the outer end of said anvil, a cap to said receptacle, a lever actuated by said external cam to reciprocate said bar, and means to feed staples to said staple-driving slide from 110 said staple-holding receptacle, all arranged to coact substantially as, and for the purpose set forth.

3. In a stapling-machine, in combination with means to hold down the article to be 115 stapled, of a framework, a revolute shaft carried by said framework, an anvil carried by said framework having a narrow-bottomed longitudinal groove in its upper face, with an upper widened apartment forming a 120 staple-holding receptacle, a reciprocating bar operative within said groove, a vertical operating staple-driving slide actuated by said bar at the outer extremity of said anvil, a cap to said receptacle, means to feed staples 125 to said staple-driving slide from said staple-holding receptacle, and means to actuate said reciprocating bar from said revolute shaft, for the purpose set forth and described.

4. In a stapling-machine, in combination with means to hold down the article to be stapled, of a framework, a revoluble shaft carried by said framework, an anvil carried by said framework having a narrow-bottomed, longitudinal groove in its upper face, with an upper widened apartment forming a staple-holding receptacle, a reciprocating bar operative within said groove, a tapering cam formed at the outer end of said bar, a vertical operative staple-driving slide actuated by said cam, a cap to said receptacle, means to feed staples from said staple-holding receptacle to said staple-driving slide, and means to actuate said reciprocating bar from said revoluble shaft, for the purpose set forth and described. 55
5. In a stapling-machine, the combination with a framework carrying a vertically-reciprocating presser-foot, of a portable anvil having a narrow-bottomed, longitudinal groove in its upper face, with an upper widened apartment forming a staple-holding receptacle, alined with and supported by said framework below said presser-foot, a cap having a center aperture and a vertical rectangular groove in the face side thereof secured to the outer extremity of said anvil, a reciprocating bar having a downwardly and inwardly sloping cam-shaped outer extremity operative within said groove and through said cap, a staple-driving slide actuated by said cam within the vertical groove of said cap, a cap to said receptacle, means to feed staples from said staple-receptacle to said staple-driving slide, and means to actuate said reciprocating bar, substantially as, and for the purpose set forth. 60
6. In a stapling-machine, the combination with an anvil having a longitudinal groove in the upper side thereof with a narrow bottom having an upper widened apartment forming a staple-holding receptacle, and a cap to said groove, of a reciprocating bar having longitudinal grooves in both its upper and lower edges, adapted to work within said groove, a staple-driving slide actuated by said reciprocating bar at the forward end of said anvil, a grooved roller fitted within an aperture intersecting said grooves near the forward end of said bar, a grooved roller fitted between depending ears at the rear extremity below said bar, a staple-feeding slide fitted within said groove above said reciprocating bar, a wire cable attached to said slide passing over said roller at the forward end of said bar and over said roller at the rear end below said bar, means to actuate said cable to feed staples to said staple-driving slide, and means to actuate said reciprocating bar, substantially as, and for the purpose set forth. 65
7. In a stapling-machine, the combination with a framework carrying a vertically-reciprocating presser-foot, of a portable anvil having a longitudinal chamber forming a staple-holding receptacle alined with and supported by said framework below said presser-foot, a cap having a vertical groove secured to the outer extremity of said anvil below said presser-foot, a vertically-reciprocating, staple-driving slide operative within the groove of said cap, means to supply staples to said reciprocating staple-driving slide, and means to actuate said staple-driving slide and advance a staple upward when said presser-foot has been lowered. 70
8. In a stapling-machine, the combination with a framework and a shaft operative within said framework, of a bracket carried by said framework at the outer extremity of said shaft, a cam operative at the outer extremity of said shaft, a vertically-reciprocative cross-head having an upper extremity adapted to play through eyelets of said bracket above said cam and a lower extremity adapted to play through an eyelet below said cam, a collar carried by said cross-head between said upper eyelets, a strap passing about said cam and having one of its ends fastened to said collar, its opposite end secured to one of said upper eyelets, friction-rollers operative from said cross-head and adapted to bear against the face-rim of said cam, a friction-roller carried by said cross-head and adapted to engage said cam to actuate said cross-head 85 downwardly, a coil-spring fitted about said cross-head below said collar adapted to operate said cross-head upwardly, and a presser-foot carried at the lower extremity of said cross-head, said strap adapted to break the recoil of said friction-roller within said cam when returning to an elevated position, all arranged to coact substantially as, and for the purpose set forth. 90
